D-14.421

UNITED STATES PATENT OFFICE.

HENRY ROST, OF MACOMB, ILLINOIS.

DESIGN FOR A MOON-DIAL FOR CLOCKS.

SPECIFICATION forming part of Design No. 14,421, dated November 13, 1883.

Application filed April 19, 1883. Term of patent 7 years.

To all whom it may concern:

Be it known that I, HENRY ROST, a resident of Macomb, in the county of McDonough and State of Illinois, have invented and produced a new and original Design for Moon-Dials for Clocks, of which the following is a specification, reference being had to the accompanying drawings, forming part thereof.

In the engraving my design in moon-dials is represented in perspective, in the foreground of which eight phases of the moon are represented, showing eight different appearances of the moon's surface, in light and dark or tinted colors, as it makes its revolution around the earth. In the fore part of the background the earth is represented by a house and trees, beyond which water or the ocean is represented. From the center of the dial to the right dark clouds are seen nearly up to the zenith of the heavens. On the left of the center the background, near the zenith, has light clouds and stars, all of which design is to represent the heavens in light and darkness, ac-

cording to the light the moon reflects upon the earth in making its revolution around it. 25

I am aware that designs in moon-dials have heretofore represented eight phases of the moon in dark and light or tinted colors; but I am not aware that a design in moon-dials has been made with eight phases of the moon having a background representing the earth, the ocean or water, and the starry heavens partly obscured by dark and light clouds. 30

Having thus fully described my invention, what I claim as new, and desire to secure by 35 Letters Patent, is—

A design for moon-dial for clocks, having eight phases of the moon in light and dark or tinted colors, with a background representing the earth, the ocean or water, and the starry 40 heavens partly obscured by dark and light clouds, substantially as described.

HENRY ROST.
